UNITED STATES PATENT OFFICE

155,523

DESIGN FOR A DISH OR SIMILAR ARTICLE

Isadore A. Lipman, Meriden, Conn., assignor to The Elmore Silver Co., Inc., Meriden, Conn., a corporation of Connecticut

Application September 11, 1947, Serial No. 141,324

Term of patent 14 years

(Cl. D44—15)

To all whom it may concern:

Be it known that I, Isadore A. Lipman, a citizen of the United States, residing in the city of Meriden, county of New Haven, and State of Connecticut, have invented a new, original, and ornamental Design for Dish or Similar Article, of which the following is a specification, reference being had to the accompanying drawing, forming part thereof, and in which:

Figure 1 is a top plan view of a dish or similar article showing my new design; and

The dominant features of the design reside in the parts shown in full lines.

I claim:

The ornamental design for a dish or similar article, substantially as shown and described.

ISADORE A. LIPMAN.
